UNITED STATES PATENT OFFICE

MCREA PARKER, OF CLEVELAND, OHIO

MEANS FOR SUPPLYING FLUID UNDER PRESSURE

Application filed February 15, 1929. Serial No. 340,230.

This invention relates to means for supplying fluid, such as air, under pressure, and more particularly to apparatus comprising, in combination, a fluid compressor and an ⁵ expansible receiver or reservoir.

Although of general application whenever fluid under pressure is required, my invention is especially designed for supplying compressed air for use in connection with ¹⁰ apparatus for producing combustible gas from gasoline or the like. Also, the expansible receiver which I preferably employ is of the floating bell or gasometer type.

Air supplying devices of this general character, as heretofore constructed, have comprised a motor driven compressor or blower, mounted on a suitable base, and connected by a pipe line with a gasometer or the like, and an automatic switch for controlling the ²⁰ motor mounted on some fixed support and operated either by fluid pressure or by the floating bell.

Such an arrangement, when employed for domestic purposes, and located, as usual, in ²⁵ the cellar or basement of a residence, has been found somewhat objectionable both on account of the space required, and of the noise and vibration made by the rapidly rotating motor and blower. Moreover, a more ³⁰ or less complicated system of piping and wiring has been required, thus entailing a relatively large expense for installation.

The object of the present invention is to provide motor driven air supplying apparatus of the character in question which shall ³⁵ be more compact and require less space than those heretofore proposed, which shall be substantially quiet and noiseless in operation, and in which the piping and wiring systems ⁴⁰ shall be greatly simplified and consequently the installation cost proportionately reduced.

With the above object in view, the invention contemplates the mounting of the ⁴⁵ motor, blower and switch directly on the floating bell itself, thus producing a single, compact, self-contained, enclosed unit, with no outside pipe connection between the blower and receiver, and to which unit current can ⁵⁰ be supplied by a flexible conductor cord

plugged into any convenient socket or outlet.

In order that the invention may be clearly understood, reference is had to the accompanying drawings, forming part of this ⁵⁵ specification, and in which:—

Fig. 1 is a vertical central section through my improved fluid compressing and storing apparatus;

Fig. 2 is a similar view but taken on a plane ⁶⁰ substantially at right angles to that of Fig. 1, namely, on the line 2—2 of Fig. 3, looking in the direction of the arrows;

Fig. 3 is a horizontal section substantially ⁶⁵ on the line 3—3 of Fig. 1; and

Figs. 4 and 5 are fragmentary sectional elevations similar to Fig. 2 but showing the parts in different positions.

Referring to the drawings in detail my ⁷⁰ improved apparatus comprises a tank or container 1 preferably formed of sheet metal and having a top or cover 2 secured thereto in any suitable way.

Enclosed within the container 1 is a floating bell or gasometer comprising a cylinder ⁷⁵ 3, also preferably formed of sheet metal, having a partition 4 extending transversely across the same near its upper end. This partition is provided with a peripheral flange 5 and is secured to the cylinder 3 as by riveting or welding. Projecting centrally upward from the partition 4 is a relatively small cylindrical housing 7 closed at its upper end as shown. This housing is for the purpose of accommodating the upper open ⁸⁰ end of a delivery pipe 8 which extends downwardly through the body of water and passes out of the container at a point near the bottom, as clearly shown in Fig. 1, for conducting the air to the carbureting device. ⁸⁵

The cylinder 3 extends a considerable distance above the partition 4, as shown at ⁹⁰ 3^a and is spaced from the walls of the container 1 by means of a plurality of guide rollers 6, placed near the top and near the bottom ⁹⁵ thereof. In order to reduce vibration and prevent the transmission of sounds, as hereinafter described, these rollers are preferably made of rubber or similar soft material which is a poor conductor of sound. ¹⁰⁰

Upon the top of partition 4 of the floating bell, and surrounding the housing 7, I place a mass or slab 9 of heavy material such as concrete or cast iron. As shown, this material consists of a concrete mass molded in situ.

The purpose of this mass or slab is to provide part of the necessary weight, and also to serve as a base on which the motor and blower or pump are mounted. The motor and pump themselves make up the remaining weight required.

The motor is designated at 10, and the pump, which is shown as a rotary blower, is illustrated at 12, the latter being driven by the former by means of a suitable belt 11. It will be observed that both the motor and pump are mounted directly upon the concrete slab 9 and are supported wholly on and move with the floating bell or gasometer.

Air is taken in to the blower through an inlet pipe having a strainer 13 at its end, and is delivered from the outlet 14. This is connected, as by means of a short piece of flexible hose 15 with the upper end of a pipe 16 which passes vertically through the partition 4 and concrete slab, the joint where it passes through the partition being rendered air tight as by means of washers and lock nuts 16^a.

This pipe may, if desired, terminate a short distance below the partition 4, but preferably it is extended downwardly to a point near the bottom of the bell, so that an effective water seal is provided, and is then bent laterally, as shown at 16^b, so as to deliver at a point near the center of the bell. Thus the air issuing from the lower end of this pipe travels upwardly through the body of water, and collects under the bell.

From the foregoing, it will be seen that the container 1 constitutes the fixed part, and the floating bell 3, 4, the movable part of a receiver of the expansible chamber type, and that the pump and motor are mounted upon the movable part of such receiver.

In order to automatically control the motor circuit so as to start and stop the blower when the pressure falls or rises to predetermined desired limits, I provide a switch, designated in its entirety by the numeral 17. This switch may be of any suitable three-position type, but preferably embodies a tilting tube containing mercury. The switch, as clearly shown in the drawings, is also mounted securely upon the concrete base 9, and is provided with a stem or column 18 projecting upwardly therefrom. Through this stem or column extends an operating rod 19. Operatively connected with the rod 19 at the upper end of the column 18 is a lever 20, having a pin and slot connection at its outer end with the lower end of a vertically extending rod 21 which passes freely through an opening in the top 2 of the con-

tainer. This rod carries a stop collar 22 which normally engages the under surface of the top 2 and is provided at its upper end with a knob or button 24. Between this knob and the top 2 is interposed a helical spring 23 surrounding the rod 21. The purpose of this will be described later.

Current is supplied to the motor by means of a flexible cord 25 passing through a suitable insulating bushing 26 in the top 2 of the container and provided at its free end with a plug (not shown) by means of which it may be connected to any convenient socket or outlet. One of the wires 25^a of this cord extends to the switch, and the other, 25^b, extends to the motor, while a conductor 27 connects the other terminals of the switch and motor, thus placing the two in series with the line.

The operation of my improved apparatus will now be briefly described. The switch being closed and the conductor cord connected to a suitable source of supply, current will flow as described and operate the motor, driving the blower 12, and deliver air under pressure therefrom through the hose 15 and pipe 16 into the interior of the floating bell 3. This will of course cause the bell to rise as compressed air accumulates in the same, and when it has risen to a predetermined limit, such for example as that illustrated in Fig. 5, the switch is automatically operated to open the motor circuit. This, as will be seen, is effected by the depression of the lever 20 by reason of the engagement of the stop collar 22 on the rod 21 with the top 2 of the container, as the bell rises.

As the air is discharged from delivery pipe 8, the bell gradually falls or sinks, until, when it has reached the normal lower limit of its movement, such, for example, as illustrated in Fig. 4, the switch is again operated by means of the lever 20 and rod 21 to close the circuit and start the blower in operation again.

It will be understood that the spring 23 is relatively stiff, and is of sufficient strength to practically anchor the rod 21 to the top 2, so far as the operation of the switch is concerned. In other words, the rod 21 remains substantially fixed as the bell rises and falls, thus serving to move the lever 20 and operate the switch as the bell reaches the upper and lower limits of its normal movement.

It sometimes happens, however, that the power supply is interrupted, and no current is available for a considerable period. If air is being used during such period it is obvious that the bell will gradually sink downward and, when the position shown in Fig. 4 is reached, the circuit will be closed. As the air continues to escape through delivery pipe 8, the bell will finally reach its abnormal low position, as shown in Figs. 1 and 2, in which its lower edge rests against the pipe 8.

As previously mentioned, air from apparatus of this character is employed to produce a combustible gas from gasoline, and it is obvious that if the burners of a stove using such gas had been left open during the period in question, the flame at such burners would, when the bell reached the position shown in Figs. 1 and 2, and the air became exhausted, become extinguished. Should the power thereafter be restored, and current be again supplied to the motor, the apparatus would automatically start up and would force combustible gas through the burners and thus into the house, with the result that disastrous effects might follow a subsequent attempt to light the burners.

In order to provide against this contingency, it is necessary to employ means so arranged that, when the bell settles to the abnormal position shown in Figs. 1 and 2, the motor circuit will be opened. This may be accomplished by the use of a separate switch, but preferably the switch 17 is so constructed that the circuit is open when the lever 20 is in either the position shown in Fig. 5, or in the position shown in full lines in Fig. 2.

After the switch has been opened by the movement of the bell to its abnormally low position, as shown in Figs. 1 and 2, it is necessary to manually close the switch again before the motor can start. This therefore constitutes a safety feature of my improved apparatus, which feature is required by the fire underwriters.

In order to manually close the switch it is only necessary to press upon the knob 24, thus forcing the rod 21 and lever 20 down into the position shown in dotted lines in Fig. 2. This, it will be seen by comparison with the position of the lever shown in Fig. 4, will serve to close the circuit, and it is necessary to hold the rod and lever in this position for a few moments until the pressure in the bell builds up to such a point as to raise it to the level shown in Fig. 4. The knob 24 may then be released and the motor and switch will continue their normal operation.

In Figs. 1 and 2, which show the apparatus with the air practically exhausted, the level of the water will be the same, both inside and outside of the bell, as shown at X. During normal operation of the apparatus, however, the water level will be higher at α outside of the bell than at γ inside of the bell. The higher the pressure within the bell the greater this difference in level, as will be seen by a comparison of Figs. 4 and 5.

From the foregoing it will be apparent that I have provided an air compressing and supplying device which is exceedingly simple in construction, compact, easy to install and safe in operation. It is also evident that the cushioning effect of the floating bell will serve to absorb the vibration due to the motor

and blower, and that the sound insulating rollers 6 will prevent the transmission of noises or vibration to the container. Thus the device is practically silent in operation.

What I claim is:

1. An apparatus for supplying fluid under pressure comprising in combination, a fluid receiver of the expansible chamber type having fixed and movable parts, and a pump and motor therefor mounted on said movable part.

2. Apparatus for supplying fluid under pressure comprising in combination a fluid receiver of the expansible chamber type having fixed and movable parts, and a pump, electric motor and switch for controlling the same, all mounted on said movable part.

3. Apparatus for supplying fluid under pressure comprising in combination, a fluid receiver of the expansible chamber type having fixed and movable parts, a motor driven pump delivering into said receiver, a switch for controlling the motor mounted on said movable part, and operating mechanism connected with said switch and anchored to said fixed part.

4. Apparatus for supplying fluid under pressure comprising in combination a unitary, portable container, and a motor, pump and floating bell gasometer all enclosed within said container.

5. Apparatus for supplying fluid under pressure comprising in combination a container, a floating bell therein, and a motor driven pump for forcing fluid into said bell, said pump being wholly supported on the bell itself.

6. Apparatus for supplying fluid under pressure comprising in combination a container, a floating bell therein, a pump, a motor for driving the same, and a switch for controlling said motor, all mounted on said bell, and means whereby said switch is operated by movement of said bell.

7. Apparatus for supplying fluid under pressure comprising in combination a container, a floating bell therein, a pump, a motor for driving the same, said pump and motor being mounted on the bell itself, a switch for controlling said motor, and means whereby said switch is operated by movement of said bell.

8. Apparatus for supplying fluid under pressure comprising in combination a container, a floating bell therein, a pump, a motor for driving the same, and a switch for controlling said motor, said switch being mounted on said bell, and operating mechanism for said switch connected with said container.

9. Apparatus for supplying fluid under pressure comprising in combination a closed container having a top, a floating bell therein, a pump, a motor for driving the same, and a switch for controlling said motor, said

switch being mounted on said bell, and operating mechanism for said switch anchored to the top of said container.

10. Apparatus for supplying fluid under pressure comprising in combination a container, a floating bell therein, a pump for delivering fluid thereto, a motor for driving said pump, a switch for controlling said motor, said switch being mounted on said bell, and operating means for said switch comprising a rod passing loosely through a wall of said container, and means for limiting the movement of said rod relative to such wall.

11. Apparatus for supplying fluid under pressure comprising in combination a container, a floating bell therein, a pump for delivering fluid thereto, a motor for driving said pump, a switch for controlling said motor, said switch being mounted on said bell, and operating means for said switch comprising a rod passing loosely through a wall of said container, and means for positively limiting the movement of said rod in one direction and yieldingly limiting it in the other.

12. Apparatus for supplying fluid under pressure comprising in combination a container, a floating bell therein, a pump for delivering fluid thereto, a motor for driving said pump, a switch for controlling said motor, said switch being mounted on said bell, and operating means for said switch comprising a rod passing loosely through a wall of said container, and means for yieldingly anchoring said rod to said wall with sufficient strength to hold it stationary so as to effect normal automatic operation of said switch as the bell moves, while permitting it to be manually shifted for emergency operation of said switch.

13. Apparatus for supplying fluid under pressure comprising in combination a container, a floating bell therein, a pump for delivering fluid thereto, a motor for driving said pump, a switch for controlling said motor, said switch being mounted on said bell, automatic means for closing said switch when the bell falls to a predetermined normal low level, and for opening said switch when said bell either rises to a predetermined normal high level or falls to an abnormally low level, and means for manually closing said switch when it has been opened by the fall of the bell to an abnormally low level.

55 In testimony whereof I affix my signature.
McREA PARKER.
